[57] **CLAIM**

The ornamental design for a combined suction nozzle and handle for use in surgical procedures, as shown and described.

DESCRIPTION

FIG. 1 is a top plan view of the handle portion of the combined suction nozzle and handle for use in surgical procedures shown in FIG. 6;

FIG. 2 is a bottom plan view thereof;

FIG. 3 is a cross-sectional view taken along the line 3—3 of FIG. 1;

FIG. 4 is an end elevational view thereof;

FIG. 5 is an end elevational view thereof, opposite that shown in FIG. 4;

FIG. 6 is a side view of a combined suction nozzle and handle for use in surgical procedures showing my new design;

FIG. 7 is a bottom plan view of FIG. 6;

FIG. 8 is a cross-sectional view taken along the line 8—8 of FIG. 6;

FIG. 9 is an end elevational view thereof;

FIG. 10 is an end elevational view thereof, opposite that shown in FIG. 9; and,

FIG. 11 is a side view of the combined suction nozzle and handle for use in surgical procedures.
